Primary Examiner — Rosemary K Tarcza*(74) Attorney, Agent, or Firm* — Holland & Hart LLP(57) **CLAIM**

The ornamental design for a charging station component, as shown and described.

DESCRIPTION

FIG. 1 is a front perspective view of the charging station component, showing my new design;

FIG. 2 is a front view of the charging station component illustrated in FIG. 1;

FIG. 3 is a rear view of the charging station component illustrated in FIG. 1;

FIG. 4 is a right side view of the charging station component illustrated in FIG. 1;

FIG. 5 is a left side view of the charging station component illustrated in FIG. 1;

FIG. 6 is a top view of the charging station component illustrated in FIG. 1; and,

FIG. 7 is a bottom side view of the charging station component illustrated in FIG. 1.

1 Claim, 7 Drawing Sheets(56)
